UNITED STATES PATENT OFFICE.

EDWIN AUSTIN COX, OF IRVINGTON, NEW JERSEY, ASSIGNOR TO THE ROTOSPEED COMPANY, OF DAYTON, OHIO, A CORPORATION OF OHIO.

STENCIL-PRINTING MACHINE.

1,117,337.

Specification of Letters Patent. Patented Nov. 17, 1914.

Application filed January 11, 1910. Serial No. 537,440.

To all whom it may concern:

Be it known that I, EDWIN AUSTIN Cox, of Irvington, in the county of Essex, in the State of New Jersey, have invented new and useful Improvements in Stencil-Printing Machines, of which the following, taken in connection with the accompanying drawings, is a full, clear, and exact description.

This invention relates to certain improvements in stencil printing machines involving the use of a rotary cylindrical segment upon which is wrapped an inking pad and a waxed stencil sheet coating with a suitable impression roller for printing the type-cut matter from the stencil upon the sheets of paper as they are fed one by one through the machine.

The main object is to increase the general working efficiency of this class of machines by simplifying and reducing the number of working parts and thereby rendering the machine less liable to impairment.

The specific objects are: First—to provide an effective means for alining the sheets as they are fed by hand, one by one, to the machine without special care from the operator. Second—to provide means moving intermittently but in synchronism with the stencil supporting segment to automatically grip the advance end of the sheet and feed it between the printing elements without liability of throwing such sheet out of alinement. Third—to drive the primary feeding means directly from one of the heads of the cylinder and to enable such head to be adjusted circumferentially relatively to the stencil supporting segment, so as to easily gage the amount of head space desired on the printed sheets. Fourth—to provide a suitable means at or to the rear of the meeting faces of the printing elements for stripping the printed sheets from the stencil.

Other objects and uses will be brought out in the following description.

In the drawings: Figures 1 and 2 are respectively a side elevation and a top plan of a stencil printing machine embodying the various features of my invention. Fig. 3 is an enlarged transverse vertical sectional view through the machine taken on line A—A, Fig. 2, showing the working parts in position just about ready to receive and print a sheet. Fig. 4 is an enlarged inner face view of a portion of one of the end

heads of the cylinder showing the means for 55 clamping the stencil supporting segment thereto. Fig. 5 is an enlarged longitudinal sectional view through the center of the machine taken on line B—B, Fig. 2. Fig. 6 is an inner face view of the gear, cam and 60 pawl for controlling the operation of the paper feeding roll and gripping device, a portion of the gear being broken away to show the slot and pin connection between the cam and gear. Fig. 7 is a sectional view 65 taken on line C—C, Fig. 6. Fig. 8 is an inner face view of the counter and its operating mechanism. Fig. 9 is a top plan partly broken away and partly in section of the presser roll, paper feed and gripping devices. Fig. 10 is an enlarged transverse sectional view taken on line D—D, Fig. 9, showing the paper gripping device as spring pressed against the periphery of the feeding roll preparatory to feeding the sheet to the 75 printing elements. Fig. 11 is an elevation of the stop mechanism for the counter.

The sheets of paper to be printed are placed upon an inclined table or support 7— between laterally adjustable guides 80 8— with their lower ends abutting one in advance of the other against a substantially horizontal support 3— from which position they are fed by hand, one by one, from the top downward against an abutment 85 4— and between suitable gripping elements consisting of a sheet feeding roller 5 and a plate 6 for alining the sheets and feeding them between the meeting faces of a suitable printing couple consisting, in this 90 instance of a rotary cylinder 7— and an underlying presser roll 8—.

The table 1— is removably inserted between upright frame sections 9— and normally rests upon a frame bar 10— below the bed plate, the inner end of the table being provided with a shoulder 11— adapted to engage any one of the teeth of an upright toothed rack 12— on the under side of the bed plate 3— to permit such 100 table to be adjusted to different angles as may be necessary to cause the different grades of paper to gravitate against the upper face of the bed plate 3—.

The upper face of the inner end of the 105 table is cut away forming a shoulder 13— which abuts against the adjacent edge of the plate 3 to allow the sheets of paper to slide

freely from the table on to the bed plate and at the same time permits the table to be readily withdrawn from its operative position and placed underneath the entire mechanism between the upright frame sections 5 —9— and upon an underlying supporting bed —14— to which the upright frame sections are secured.

The table —1— and bed plate —3— are 10 located some distance to one side of the meeting faces of the printing elements leaving ample intervening space for the operation of the abutment —4— and gripping element —5— both of which latter are secured together upon and to a rotary shaft —15—.

The gripping elements —5— and —6— are substantially coextensive in length with that of the bed plate —3— and are disposed in planes one above the other with a normal 20 intervening clearance or space in the same horizontal plane as the upper face of the bed plate —3— to permit the advance end of the sheet to pass through said clearance and against the abutment —4— which is 25 also normally disposed in the same plane and parallel with the axis of the printing elements. The feeding element —5— consists of a substantially semi-circular segment of rubber vulcanized or otherwise secured to one of two clamping plates —16— which are clamped upon opposite faces of the shaft —15— by screws —17—, the periphery of the feeding element —5— being eccentric to its axis of rotation so as to 30 more effectually grip the sheet and feed it to the printing couple.

The gripping element —6— consists of metal plate secured to a rock shaft —18— in a plane just above the bed plate —3— parallel with the meeting faces of the printing elements leaving sufficient clearance between it and the bed plate —3— to allow the passage of a sheet to be printed thereunder.

The rear edge of the gripping element 45 —6— is normally held a slight distance above the feeding element —5— by a pawl —19— and a movable detent —20— but is forced into contact with the end of the paper which rests upon the feeding element 50 —5— by a spring —21— when the pawl is released by the tripping of the detent in a manner presently described. The spring is coiled around one end of the shaft —18— with its opposite ends engaged respectively 55 with the adjacent frame section —9— and gripping element —6—.

The detent —20— consists of a fiber disk 60 loosely mounted upon one end of the shaft —15— and provided with a cam tooth —22— having an abrupt termination and upon which the end of the pawl —19— normally rests, as clearly shown in Fig. 6. This disk or detent is connected with a lost motion to a fiber gear —23— which is 65 rigidly secured to the same shaft, the gear

being provided with a pin —24— projecting laterally into a circumferential slot —25— in the disk —20— to allow the disk to move a limited distance independently of the gear sufficiently to release the pawl —19—, the pin —24— being held against one end of the slot by a light coil spring —26— which is interposed between the pin and opposite end of the slot.

The cylinder —7— consists of a perforated 75 cylindrical segment —27— of sheet metal and opposite end heads —28— and —29—, the latter having annular grooves —30— on their inner faces for the reception and retention of the ends of the segment —27—.

The heads —28— and —29— are centrally journaled upon short axial stubs —31— on the upper portions of the frame sections —9—, the head —28— being provided upon its periphery with a toothed rack —32— having a number of teeth corresponding to and adapted to mesh with the gear —23— which is provided with a concave face —33— concentric with and riding against the periphery of the head —28—, so as to allow 90 the shaft —15— with the gripping element —5— and gear —23— thereon to remain at rest during the revolution of the cylinder except when the teeth of the rack —32— are brought into registration with those of 95 the gear —23—.

The cylinder —7— is rotated continuously by means of a hand crank —34— and intermeshing gears —35—, the crank arm —34— being journaled on one of the frame 100 sections —9— and secured to one of the gears —35— while the other gear is secured directly to the hub of the cylinder head —28—.

The stencil supporting segment —27— is 105 substantially semi-circular and perforated throughout the greater portion of its area and is provided with circumferential grooves —39— at opposite sides of the perforated portion for receiving the inner ends of 110 stripper fingers —40—, which are secured to a frame bar —41—. These stripper fingers extend rearwardly from between the meeting faces of the printing couple to engage and strip the advance ends of the sheets 115 from the stencil during the operation of printing.

The cylinder head —28— is adjustable circumferentially relatively to the stencil supporting segment —27— for the purpose of 120 operating the paper feeding device earlier or later in the travel of the advance end of the stencil segment, so as to vary the amount of head space on the printed sheets and is held in its adjusted position by a 125 segmental spring metal strap —42— and a hand rotated cam or eccentric —43— seated in a loop —44— in the central portion of the strap —42—, which strap bridges across the space between the circumferential 130

ends of the stencil supporting segment and is secured at its ends by brazing or otherwise to the adjacent edges of said segment.

The cam —43— is provided with a hand piece —45— movable within the periphery of the cylinder and when moved to one position allows the opposite arms of the band —42— to spring inwardly and unlock the head for adjustment, and when rotated in the opposite direction distends said band thereby frictionally locking the head —28— to the stencil supporting segment. In the drawings I have shown an additional strap —42— in the groove —30— of the opposite head for the same purpose and operable in the same manner as that previously described so that either head may be adjusted relatively to the segment or the segment may be adjusted relatively to either head if desired.

At the proper time during the rotation of the stencil cylinder and after one of the sheets, as —a—, has been fed forwardly by hand with its advance end engaged with the alining abutment —4—, the detent —20— is tripped by a pin or shoulder —70— projecting laterally from the outer side of the cylinder head —28—, said pin engaging a shoulder —68— on the periphery of the disk —20— similar to but just in advance of the cam tooth —22—. This pin —70— and the shoulder —68— on the disk —20— with which it engages are so relatively positioned as to cause the pin —70— to rotate the disk —20— just enough to allow the end of the pawl or finger —19— to drop off from the cam tooth 22 thereby permitting the gripping element —6— to be depressed and thus press the advance end of the sheet —a— against the upper face of the gripping element —5—. The detent —20— is now at the limit of its movement independently of the gear —23— as determined by the pin —24— and slot —25—, the detent —20— being held against the action of the spring —26— by the engagement of the finger —19— with the cam tooth —22—. Immediately following this tripping of the detent 20, the cam tooth —22— is engaged by a separate pin —71— also projecting laterally from the end face of the cylinder head —28— for additionally rotating said detent 20 and gear —23— and thereby causing the teeth of the latter to mesh with the toothed rack —32— which serves to rotate the feeding element —5— one revolution or sufficient to feed the advance end of the paper between the stencil segment —27— and presser roll —8—.

The circumferential ends of the stencil supporting segment —27— are bent inwardly in the form of V-shaped loops disposed at slightly less than right angles to the adjacent portions of the segment with their open sides facing outwardly, for re-

ceiving the ends of the inking pad and stencil and suitable retaining bars by which the said inking pad and stencil are held in operative position, as best seen in Fig. 10. The edges of the loops nearest to each other 70 terminate in substantially the same plane as the periphery of the segment so as to better retain the locking bars in the loops.

The presser roll —8— which is made of rubber is mounted upon a rotary shaft 75 —50— having its end journaled in vertically movable plungers —51— which are connected by springs —52— to the upper portions of the frame —9—, as best seen in Fig. 5, so as to yieldingly hold the presser 80 roll against the stencil during the operation of printing.

When the machine is not in use the plungers —51— together with the presser roll —8— may be drawn downwardly away 85 from the cylinder by means of eccentrics —53— which ride against suitable bearings —54— on the frame sections —9— and are connected by an operating shaft —55— having a hand crank —56— at one end 90 whereby the eccentrics may be operated. One of the eccentrics is provided with a laterally projecting pin —57— adapted to engage one side of the plunger to limit the degree of rotation of the eccentric. 95

It is now apparent that the feeding roller —5— is rotated intermittently one complete revolution during a comparatively small portion of each revolution of the cylinder while the toothed segment —32— is 100 in mesh with the gear —23— and that this feeding movement is just sufficient to assure the proper entry of the advance end of the sheet between the printing elements which latter continue to feed and print the sheet 105 after the rotation of the feeding element —5— has ceased. As the sheets are printed and fed from between the printing elements, they are deposited by gravity upon a receiving plate —58— which is provided at 110 its outer end with a stop shoulder or abutment —59— and is adjustable vertically and longitudinally in suitable slots —60— in the inner sides of the opposite frame sections —9—, such adjustment depending 115 somewhat upon the quality of paper used and also upon the speed of action of the machine.

The number of sheets printed may be registered by any well known form of counting 120 mechanism, as —61— having an operating arm —62— which is yieldingly connected by spring —63— to a connecting rod —64—, the latter being eccentrically connected to one of the gears —35—, as best 125 seen in Fig. 8.

Portions of the surfaces of the paper supporting table and horizontal bed —3— are roughened by the application of sand paper or similar material thereto to hold all ex- 130

cept the uppermost sheet of paper against forward movement when such upper sheet is fed by hand to the feeding device.

In operation the sheets to be printed are stacked upon the inclined table —1— in which position they gravitate or slide against the upper roughened surface of the bed-plate —3—, the uppermost sheets being in advance of the others whereupon, when the stencil supporting cylinder is rotated by the hand crank —34—, the uppermost sheet is fed forwardly between the gripping elements —5— and —6— until its front edge butts against the abutment —4— which alines the sheet preparatory to feeding it to the printing couple during which operation the pawl —19— rests upon the point of the cam tooth —22— to hold the gripping element —6— slightly above the gripping element —5—, so as to allow free passage of the sheet between said gripping elements and against the abutment —4—. Now as the stencil supporting drum continues to rotate, the shoulder —70— will first engage the shoulder —68— and move the detent or cam disk —20— sufficiently to allow the pawl —19— to drop off from the end of the cam tooth —22—, thereby permitting the gripping element —6— to press the underlying end of the sheet against the adjacent face of the gripping element —5—, said cam disk —20— being moved such limited distance relatively to the gear —23— against the action of the spring —26— where it is temporarily held against returning by the engagement of the end of the pawl —19— with the cam tooth —22—. Immediately following this operation, the cam tooth —22— is engaged by the pin —71— on the cylinder head —28—, the object of which is to rotate both the cam disk —20— and pinion —23— sufficiently to bring the teeth of the pinion into mesh with the toothed rack —32— on the cylinder head —28— whereupon positive rotary motion is imparted to the pinion and also to the eccentric gripping element —5— which is secured to the same shaft —15— as the pinion.

The relative number of teeth on the toothed rack —32— and pinion —23— is such as to cause one complete rotation of the feeding element —5— to frictionally feed the sheet of paper between the meeting faces of the presser roll —8— and stencil supporting segment.

As previously described, the head —28— carrying the toothed segment —32— is adjusted relatively to the stencil supporting segment —27— so as to feed the advance end of the sheet the desired distance across the upper face of the presser roll before the printing from the stencil takes place, thereby permitting more or less head space to be left on the printed sheet as may be desired.

Immediately upon the entrance of the sheet between the printing couple, the ends

of the stripper fingers which lie just above the sheet operate to strip the sheet from the cylinder as it is fed toward the rear of the machine.

The particular function in effecting one complete revolution of the feeding device —5— is to insure the feeding of the end of the paper between the meeting faces of the printing couple or until the advance end of the stencil is brought into coaction with the presser roll —8— to grip and continue to feed and print the sheet, the printing sheet being discharged at the rear of the printing couple upon the receiving plate —58—. As soon as the gripping and feeding device —5— has completed one revolution, it is held against further movement during the printing operation by the engagement of the smooth periphery of the head —28— with the concave face —33— of the gear, such concave face being concentric and coincident with such periphery. As soon as the pinion begins to rotate from its normal position, the spring —26— returns the cam disk —20— to its normal position relatively to such pinion and therefore also rotates one complete revolution thereby riding under the end of the pawl —19— to elevate the latter and thus elevate the gripping plate —6— a slight distance from the periphery of the gripping element —5—, whereupon the operation of feeding another sheet to the machine may be repeated.

The counter —61— is prevented from counting when the presser roll —8— is drawn away from the stencil supporting drum by means of a link —80— having its upper end pivoted at —81— to the free end of the counter operating lever, as —62—, and its opposite end provided with a lengthwise slot —82— receiving the cam shaft or spindle —55—, the lower end of the slot being closed to form an abutment or limiting stop adapted to be engaged by the spindle —55— when the latter is rocked downwardly in drawing the presser roll —8— away from the stencil supporting drum, thereby holding the counter lever —62— against upward movement, should the drum be rotated when the presser roller is not in its operative position. Under such conditions the link —64— is free to move lengthwise thereby tensioning and compressing the spring —63— without operating the counter lever —62—.

What I claim is:

1. In a stencil printing machine, a rotary drum comprising a cylindrical stencil supporting portion, and a head to support said cylindrical portion, said parts being rotarily adjustable relatively one to the other, and sheet feeding means driven by said head.

2. In a stencil printing machine, a drum comprising a supporting segment, and sup-

- porting heads at the opposite ends of said segment, one of said heads and said segment being adjustable relatively one to the other, and sheet feeding means actuated by one of said heads.
5. In a stencil printing machine, a rotary drum having a stencil supporting segment, segment supporting heads at the opposite ends thereof, one of said heads being adjustable rotarily relatively to the segment, means for clamping the adjustable head in its adjusted position, and means actuated by the adjustable head.
6. In a stencil printing machine, a rotary drum having a stencil supporting segment and opposite end heads, one of said heads being adjustable rotarily relatively to the segment, an expansible and contractible arcuate bar connected to the segment for frictional engagement with the adjustable head, said bar being formed with a radially extending loop, and a cam operating in said loop to expand the bar against said head to lock the latter in an adjusted position to the segment.
7. In a stencil printing machine, a rotary drum having a stencil supporting segment, and segment supporting heads at the opposite ends thereof, one of said heads and said segment being capable of relative rotary adjustment, a frictional clamping device to retain said parts in their adjusted positions, and sheet feeding means actuated by said head.
8. In a stencil printing machine, rotary sheet feeding means, a rotary drum having opposite end heads and a stencil supporting segment mounted on said heads, one of said heads being capable of rotary adjustment relatively to said segment, and means co-acting with said adjustable head for transmitting rotary motion to said sheet feeding means.
9. In a stencil printing machine, sheet feeding means, a rotary printing couple, means actuated by one of the members of said couple for intermittently operating the sheet feeding means comprising a rack on said member, and a coacting mutilated pinion having its mutilated portion concentric with the axis of said member when not engaged by the rack.
10. In a stencil printing machine, a rotary stencil supporting drum having a toothed rack and a stencil segment adjustable rotarily relatively to the rack in combination with paper feeding means actuated intermittently by said rack once during each revolution of the drum, and means to rotate the drum.
11. In a stencil printing machine, a rotary printing couple, coacting paper gripping elements, one of which is rotatable to feed the paper to said couple, the other element being non-rotatable and spring pressed to- ward the rotatable element, means for rotating one member of said couple, and cooperating devices connected respectively with said member and said rotatable gripping element to control the action of said gripping elements, said devices comprising a rack and a mutilated gear.
12. In a stencil printing machine, a printing drum having a rotarily adjustable part, means including an expansible and contractile member for locking and releasing said adjustable part, and sheet feeding means actuated by the drum.
13. In a stencil printing machine, a printing drum having a stencil supporting segment, means including a strap and eccentric for clamping the segment to the drum, and sheet feeding means actuated by the drum.
14. In a stencil printing machine, a rotary printing couple and actuating means therefor, a rotary paper feeding element provided with an abutment against which the sheets of paper are fed by hand, a gripping element spring pressed toward the feeding element, means for holding the gripping element apart from the feeding element, additional means rotating with one of the printing elements for tripping the holding means, and further means comprising a rack, and mutilated gear for rotating the feeding element after the gripping element has been released.
15. In a stencil printing machine, a printing drum having one of its end heads adjustable rotarily and means controlled by such head for gripping and feeding the sheets to be printed one by one to the printing drum and including a rotary eccentric.
16. In a stencil printing machine, sheet feeding mechanism having a mutilated pinion in combination with a rotary printing drum having a toothed segment for operating the pinion intermittently one revolution at a time, said drum having means coacting with the mutilated pinion to hold the latter against rotation when not actuated by the toothed segment.
17. In a stencil printing machine, a rotary printing couple and actuating means therefor, a paper feeding roll having an abutment for alining the ends of the sheets to be printed in the machine, a presser plate coacting with the feed roll to grip the paper, means normally holding the presser plate away from the feed roll and separate devices rotating with one of the printing elements for tripping the holding means for the presser plate, and for rotating the feeding roll one complete revolution at each revolution of such printing element, the last mentioned device comprising a toothed rack cooperating with a mutilated gear connected with said feed roller.
18. In a stencil printing machine, sheet feeding means comprising a roller having

an abutment for the advance ends of the sheet and a mutilated pinion, a rotary printing drum having a toothed segment coacting with the pinion to rotate the feeding roller 5 one revolution at a time, said drum having means coacting with the mutilated portion of the pinion for holding the roll against rotation when not actuated by the toothed segment, said segment being adjustable rotarily to vary the time of action of the feeding mechanism.

17. In a stencil printing machine, a printing couple comprising a stencil supporting segment, a rotary head having a portion of its periphery toothed and its remaining portion smooth, and a coacting presser roll in combination with an intermittently rotatable feeding roll, a pinion having a concave bearing for said smooth portion of the head for 15 holding the feeding roll against rotation during a partial rotation of the stencil supporting segment, said pinion being connected to the feed roll and engaged by the toothed portion of the head for rotating 20 said feed roll one complete revolution at each revolution of the stencil supporting segment.

18. In a stencil printing machine, a rotary stencil supporting segment and coacting presser roll, mechanism for gripping and feeding the sheets of paper to be printed one by one to the printing couple, said mechanism including a feeding roll and a presser plate spring pressed toward the roll but 25 normally held apart therefrom, means including a cam and pawl for holding the presser plate in its inoperative position, said cam having a limited movement independ-

ently of the feed roll, means rotatable with the stencil supporting segment for engaging and moving the cam to trip the pawl and release the presser plate, and additional means also rotating with the stencil supporting segment for rotating the feed roll after the presser plate has been released. 40 45

19. A stencil printing machine comprising a drum having a stencil supporting segment provided with circumferential grooves in its periphery, a presser roll coacting with the portion of the segment between the 50 grooves, sheet feeding mechanism located in front of the meeting faces of the drum and presser roll, and stripper fingers extending rearwardly from the meeting faces of said drum and roll and having their free ends 55 entering the grooves in the segment.

20. In a stencil printing machine, a printing couple consisting of a drum and presser roll, the drum being provided with a stencil supporting segment having circumferential 60 grooves in its periphery near the ends thereof, a toothed segment on the drum adjustable rotarily thereon, sheet feeding mechanism actuated by said segment, and stripper fingers extending rearwardly from the 65 meeting faces of the printing couple and having their free ends entering the grooves in the segment.

In witness whereof I have hereunto set my hand on this twenty-seventh day of December 1909.

EDWIN AUSTIN COX.
